J. W. COSGROVE

CEMENTING MACHINE

Filed April 27, 1922

UNITED STATES PATENT OFFICE.

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY.

CEMENTING MACHINE.

Application filed April 27, 1922. Serial No. 556,870.

This invention relates to cementing machines, and more particularly concerns apparatus for applying adhesive to the tops of tennis or like rubber-sole shoes. These tops are sometimes formed with the edges about the toe-portions scalloped, so that in lasting these over the insoles, they will lie more smoothly, due to the absence of protuberances in the gathered-in material. In cementing such tops for their attachment to the insoles, it is desired that over the scalloped portion the work shall be coated to the full depth of the projections and over some of the adjacent material inside their bases, and that beyond these scallops the edge shall receive a band of the adhesive of less width. This operation presents difficulties, because the projections from the body of the material are easily displaced or twisted, leading to their being cemented together in this position, in which they do not properly extend over the insole in lasting. Then, too, the applying member operating over the projections also acts between them, and tends to deposit cement upon the co-operating pressure or work-supporting member. The last-mentioned effect is further produced during the operation upon the narrower area at each side of the scallops. This daubing of the pressure member piles cement up at the bases of the scallops, causing objectionably uneven coating.

My invention has as an object the provision of a machine by which work having the above-described or similar characteristics may be coated uniformly and without distortion. In the attainment of this object, a coating member and the work are held in applying relation with less pressure over the projections than over the body of said work. In carrying out this operation, I preferably combine with a rotatable cement-applying member a rotatable work-engaging pressure member and an associated work-engaging member fixed relatively to the rotatable member and separated from the applying member by a greater distance than is said rotatable member. This arrangement permits a positive advance of the work by the firm contact of the applying member and rotatable pres-

sure member with it, especially over the continuous portion, while the companion engaging member may touch the projections of the scallops so lightly that they will not be displaced, though held closely enough to the applying member to receive their coating. Moreover, the extent of separation between the applying member and this fixed member prevents the latter from gathering cement and delivering it irregularly to the work. Preferably, both the applying member and rotatable work-engaging member, the latter supporting the work in the present embodiment of the invention, are in the form of rolls driven to advance the work, while the associated work-engaging and supporting member may consist of a rigid finger, which, once properly related to the work, will perform its functions unfailingly and without attention.

Another object of the invention is to facilitate the correct presentation of the work to the applying member by the operator. For this purpose, there is associated with the applying member and the plural pressure members a gage, having means for guiding the work in contact with both pressure members and means arranged to guide said work in contact with but one of the pressure members. In the first instance, the full width, including the projections and the adjacent body of the material, may be coated, while in the second, the narrower band at each side of the scallops may be applied. This gage is shown as extending in front of the applying and pressure members, with respect to the presentation of the work thereto, and provided with two substantially vertical work-guiding surfaces separated transversely of the direction of feed.

The improved method of treating flexible sheet material disclosed herein is claimed in my copending application Serial No. 178,435, filed March 25, 1927, which is a division of the present application.

In the accompanying drawings, illustrating a particular embodiment of the invention,

Figure 1 shows my improved cementing machine in front elevation;

Fig. 2 is an end elevation looking from the left in Fig. 1;

Fig. 3 is a perspective view of the gage and work-supporting finger; and

Fig. 4 illustrates a portion of a top which has been cemented by the machine.

- 5 Generally, the apparatus may be as disclosed in the patent in my name No. 1,380,360, dated June 7, 1921. This has, supported upon a frame 10, a receptacle 12 for delivering cement or other adhesive to an applying 70 roll 14. The applying surface of this roll may have projections 16 extending in series both circumferentially and laterally of the roll, between which projections are intermediate spaces, serving as pockets to hold the 75 cement which is laid by the points of the projections upon the surface to be coated. The width of this surface is such as to make the application of cement to the maximum width of the area to be coated. A piece of the work 80 is indicated at T in Fig. 4 of the drawings, this being the toe-portion of the top of a tennis shoe. About it are projections *a*, between which are curved depressions *b* forming a series of scallops, which gradually decrease in 85 depth from points near the forward extremity of the toe to those at each side. The full height of these scallops is to be coated, and also a band at *c* within their bases, this band, beyond the toe-portion, extending at each 90 side of the top at *d* and being narrower than the width of the coating applied to the scalloped portion.
- 95 The applying roll 14 is fixed upon the outer end of a shaft 18 rotatable in the frame and driven from a suitable source of power. Pivoted upon the frame, below the shaft 18, is an arm 20, in which is rotatably mounted a shaft 22 also driven and having secured to it, beneath the roll 14, a pressure and work-supporting roll 24. The arm with the shaft and roll may be raised to bring the latter into co-operation with the applying roll by treadle or spring mechanism (not illustrated), the upward movement being limited 100 by a stop screw 25 carried by the arm and contacting with the overhanging portion of the frame. As here shown, the roll 24 is arranged with its outer edge outside the corresponding edge of the applying roll 14, and it 105 extends beneath said roll to an amount at least substantially equal to the width of the coated area *d* upon the work. Adjacent to the roll 24, at its inner side, is an associated pressure and work-supporting member, preferably consisting of a finger 28, which may be of cast metal or other rigid material, this finger having a supporting shank 29, from which it curves upwardly and rearwardly substantially concentric to the periphery of 110 the roll 24. Its width is at least a substantial portion of the maximum depth of the scallops. In the present embodiment of the invention, this finger is mounted upon a block 30, which also furnishes a work-gage and which is carried by the arm 20. To this it is 115 secured by a screw 32 passing through a horizontal slot 34 in the block and threaded into the arm. By this mounting the gage-block may be varied in its position with relation to the applying roll to change the width of the 79 area to be coated. To the rear of the block the shank 29 of the finger is fixed by screws 36, 38 passing through slots 38 in the shank and engaging the block. This slot-and-screw connection furnishes an adjustment for the 75 finger toward and from the applying roll; but once the correct position is determined, this may remain unchanged. The proper location for the finger in the performance of the work for which this apparatus is particularly designed is just below the adjacent periphery of the roll 24, so that the cement carried by the applying roll 14 will at all times be out of contact with the finger, and the work between the finger and applying roll 85 will be subjected to less pressure than that portion between said applying roll and the supporting roll 24. Upon the block 30 are two substantially vertical work-guiding surfaces 40 and 42, the former being shown nearly in vertical alinement with the inner edge of the applying surface of the roll 14, while the surface 42, which is at the outer end of the block, is shown adjacent to the side of the roll 24. The distance between the guiding 90 surface 40 and the outer edge of the applying roll corresponds to the maximum width of the area to be coated, including the projections and the band *c* within them. When the surface 42 is employed as a guide, the space 100 coated is that indicated at *d*.
- 95 In using the machine, the operator may start at the heel-portion of the top, and employing the surface 42 as a gage, moving the outer edge of the work against this or in vertical alinement with it, may advance the end of the work between the rolls 14 and 24, which, in their rotation, feed it forward, the former applying to it a coating of cement from the receptacle 12 to cover the area *d*. 105 In this connection, the finger 28 is inactive, being beyond the edge of the work, but is sufficiently removed from the cement-laden surface of the roll 14 so that it is not daubed by it. As the scalloped portion at the toe is approached, the operator shifts the work laterally between the rolls until its edge is directed by the surface 40. At this time, both the roll 24 and the finger 28 are effective to maintain the material in engagement with 110 the applying roll, the projections of the scallops being held with so little pressure against said roll that they are not displaced, and the separation between the roll and finger keeping the latter clean during the passage of the 115 depressions *b*. Having rounded the toe-portion, the work is again moved laterally to utilize the surface 42 as a guide and complete the coating of the narrower area *d* at the opposite side.

Having described my invention, what I claim as new and desire to secure by Letters Patent of the United States is:

1. In a cementing machine, a rotatable cement-applying member, a work-supporting roll co-operating with the applying member, a work-gage situated at one side of the work-supporting roll, and a rigid work-supporting finger situated opposite the applying member between the gage and roll with its work-supporting surface at a different distance from the applying member than is such surface of said roll. 70
2. In a cementing machine, a rotatable cement-applying member, a work-supporting roll co-operating with the applying member, a work-gage situated at one side of the work-supporting roll, and a rigid work-supporting finger situated opposite the applying member between the gage and roll with its work-supporting surface farther from said applying member than is the supporting surface of said roll. 75
3. In a cementing machine, a cement-applying roll, a co-operating work-supporting roll, means for rotating said rolls to advance the work, and a work-supporting member situated adjacent to the supporting roll and opposite the applying roll, said member being fixed relatively to the supporting roll in a position farther from the applying surface than is the supporting roll. 80
4. In a cementing machine, a cement-applying roll, a co-operating work-supporting roll, means for rotating said rolls to advance the work, a work-gage, and a work-supporting finger situated between the supporting roll and gage. 85
5. In a cementing machine, a cement-applying roll, a co-operating work-supporting roll, means for rotating said rolls to advance the work, and a work-supporting finger fixed adjacent to the supporting roll and opposite the applying roll and at a greater distance from the applying roll than is the supporting roll. 90
6. In a cementing machine, a cement-receptacle, an applying roll rotatable at the bottom of the receptacle, an arm pivoted below the applying roll, a shaft journaled in the arm, means for driving the shaft, a work-supporting roll carried by the shaft opposite the applying roll, a work-gage mounted upon the arm, and a work-supporting finger fixed to the arm between the gage and supporting roll and extending opposite the applying roll. 95
7. In a cementing machine, a cement-receptacle, an applying roll rotatable at the bottom of the receptacle, an arm pivoted below the applying roll, a shaft journaled in the arm, means for driving the shaft, a work-supporting roll carried by the shaft opposite the applying roll, and a work-supporting finger fixed to the arm and extending opposite the applying roll adjacent to the sup- 100
- porting roll, said finger being at a greater distance from the applying surface than is the supporting roll. 105
8. In a machine for cementing the scalloped edges of shoe-tops, a cement-applying roll of a width greater than the maximum depth of the scallops, a pressure member co-operating with the applying roll and extending transversely of the work for a substantial portion of the maximum depth of the scallops, and a pressure member co-operating with the applying roll and arranged for contact with the top-material inside the bases of the scallops. 110
9. In a machine for cementing the scalloped edges of shoe-tops, a cement-applying roll of a width greater than the maximum depth of the scallops, a pressure member co-operating with the applying roll and extending transversely of the work for a substantial portion of the maximum depth of the scallops, and a pressure member co-operating with the applying member and arranged for contact with the top-material inside the bases of the scallops, the first-mentioned pressure member having its work-engaging surface at a greater distance from the applying surface than is the work-engaging surface of the associated pressure member. 115
10. In a machine for cementing the scalloped edges of shoe-tops, a cement-applying roll of a width greater than the maximum depth of the scallops, a pressure-finger co-operating with the applying roll and extending transversely of the work for a substantial portion of the maximum depth of the scallops, a pressure-roll co-operating with the applying roll and arranged for contact with the top-material inside the bases of the scallops, the work-engaging surface of the pressure-finger being at a greater distance from the applying surface than is the work-engaging surface of the pressure-roll, and means for rotating the applying roll and pressure-roll to advance the work. 120
11. In a cementing machine, a cement-applying member, two pressure members for holding the work in engagement with the applying member, and a gage having means arranged to guide the work in contact with both pressure members and means arranged to guide said work in contact with one pressure member only. 125
12. In a cementing machine, a cement-applying member, a pressure member for holding the work in engagement with the applying member, and a gage extending in front of said members and provided with a plurality of work-guiding means. 130
13. In a cementing machine, a cement-applying member, a pressure member for holding the work in engagement with the applying member, and a gage extending in front of said members and provided with two substantially vertical work-guiding surfaces

separated transversely of the direction of feed.

14. In a coating machine, an applying member, a plurality of pressure members for holding the work in engagement with the applying member, and means having a portion arranged to guide the work in contact with plural pressure members and a por-

tion arranged to guide said work in contact with a different number of pressure members than are made effective by the first-mentioned portion.

In testimony whereof I have signed my name to this specification.

JOHN W. COSGROVE.
